UNITED STATES PATENT OFFICE.

LUTHER L. BOSWORTH, OF CLEVELAND, OHIO.

ELECTRICAL DENTAL FURNACE.

SPECIFICATION forming part of Letters Patent No. 781,762, dated February 7, 1905.

Application filed March 5, 1904. Serial No. 196,767.

To all whom it may concern:

Be it known that I, LUTHER L. BOSWORTH, a citizen of the United States, residing at Cleveland, in the county of Cuyahoga and State of Ohio, have invented certain new and useful Improvements in Electrical Dental Furnaces; and I do declare that the following is a full, clear, and exact description of the invention, which will enable others skilled in the art to 10 which it appertains to make and use the same.

My invention relates to electrical dental furnaces; and the invention consists in a furnace constructed and adapted to operate substantially as shown and described, and particularly pointed out in the claims.

In the accompanying drawings, Figure 1 is a perspective view of the furnace complete and assembled for use. Fig. 2 is a perspective view of the earthen body and its casing and 20 with the end B and the muffle members F and G removed. Fig. 3 is a perspective view of the outer muffle member or section, and Fig. 4 is a perspective view of the inner muffle member or section. Fig. 5 is an enlarged longitudinal sectional elevation of the furnace with its parts assembled as in Fig. 1; and Fig. 6 is a cross-section thereof on line *x x*, Fig. 5.

In the development of the furnace as thus shown I have had especially in mind a construction which will reduce the operating expense to the minimum and make the furnace easy to repair when it burns out or is otherwise damaged in use.

Hitherto in dental furnaces with have come 35 under my observation and are in more or less general use among dentists there has been very great annoyance and expense attending the operation of the same because the heating-wire is embedded in the muffle, and hence re- 40 pair of the wire is impossible. Nothing but a new muffle will do, and this is expensive as an article and annoying to obtain because it has to be gotten from the factory and often involves weeks of delay. By my improved 45 construction I provide a separable muffle with the platinum wire exposed, so that it can be easily repaired and the user of this furnace can himself make such repairs without any material delay. My experience has been that 50 owing to the very intense heat in a furnace

of this kind the platinum wire cannot endure more than comparatively few minutes before it burns out at some point, and I claim no immunity for the wire by my construction; but what I do claim is a construction which enables a dentist or other user of the furnace to 55 make the repairs on the spot and inexpensively, and resume the use of the furnace in a very brief time after a burn-out has occurred.

Referring to the drawings, the invention is 60 embodied in a casing or shell comprising a cylindrical body A and two ends B B', secured upon the said body in any suitable way, and provided with legs b, which serve as supports. Usually end B is removable and end B' may 65 be also, but not necessarily.

C is a fire-clay or like refractory body 70 inclosed within the shell or casing and constituting a support for a resistance-coil about the same, as well as providing a muffle-receiving cavity c in one end, which is also referred to herein as an "oven." The said body C is preferably made up as a separate article of manufacture for my use, and may be constituted of fire-clay or any other suitable material 75 which has firmness enough to hold its shape and is reasonably light in weight. I do not, therefore, limit myself to fire-clay for this purpose, nor to the manner of providing said body, as I can build it into its windings from 80 plastic material which will harden for use. The said body is a part of somewhat less cross-section than the interior of the casing and has two convolutions or windings of resistance-wire D spirally around the same from end to 85 end, the inner convolution or winding being directly upon the said body itself and the outer winding upon or about an asbestos or equivalent non-conducting covering or jacket c', fitting closely about body C. Then there 90 is a wall c² of asbestos or the like interposed between body C and the metallic shell without, so that said parts are completely insulated from each other electrically.

The terminals 2 and 4 of the resistance coils 95 or wire D are at the front end of the furnace, and current-conductors 5 and 6, such as wires or the like, extend through head B' at the rear and body C and are provided with binding-posts or the like at their rear ends to connect 100

the line-wires. At their opposite or front ends connections are made between conductor 5 and terminal 2 of the resistance-wire, and further connection is made between conductor 5 6 and terminal 4 by interposed muffle-heating platinum coil or winding H. Thus end h of winding H is detachably connected with conductor 6 and h' with terminal 4, thereby completing the line-circuit. The current enters 10 through conductor 5 and leaves by conductor 6.

It has been observed that refractory body C is provided with an oven c and said oven is substantially triangular in cross-section, with one side forming the bottom of the oven and 15 the other two sides the converging walls and roof thereof, and the said oven tapers gradually inward to produce a substantially conical opening smallest at its rear.

The muffle consists of two sections F and 20 G, which are adapted to occupy cavity or oven c, and these are telescoped or sleeved one upon or over the other—that is, the outer or inclosing section F wholly envelops and incloses the inner one about its side and 25 extremity and constitutes a wall just within the wall of the oven for the inner section, but is removable with section G. Hence in a practical sense said outer section constitutes a protecting and working jacket for the inner 30 one, and by using a double and separable muffle I am enabled to get all the advantage of a single muffle with the heating-wire embedded therein, but obtain the added and very natural advantage of having the wire within reach 35 when it burns out and should be repairable. In such case the inner muffle-section is simply withdrawn from the outer one and the broken wire is openly exposed and can be quickly mended. Head B of the casing has a triangular hole b' formed centrally therein directly 40 in front of the oven and corresponding thereto, but of a size approaching more nearly to the internal dimensions of the inner muffle-section, so that when the muffle is deposited in 45 the oven and the front plate or head B is put in place it serves to confine the muffle in working position. A hearth-plate b² is secured upon head B in front of the oven at the lower edge of opening b' and an isinglass or other 50 closure is employed to temporarily close the oven and confine the heat.

The two muffle-sections F and G are preferably made of Hessian sand or other refractory material of very high heat resistance and 55 which is firm and strong in service, and asbestos or equivalent non-heat-conveying lining 9 is interposed between outer section F and the wall of the oven. The inner muffle or muffle-section G is tightly wound with a 60 preferably platinum heating-wire H and the inner end h thereof is wrapped across the end of said section and passed through a hole in the rear portion of the outer section, Fig. 3, whence it is carried forward from the back of 65 said section for convenient connection with

one of the terminals or current connections of the resistance-coil about body C. The other end, h', of wire H is connected with the other terminal of the resistance-coil, and both connections are thus brought conveniently just 70 inside the head B. The said head or plate is removably secured in place by any convenient means and is shown as having a rim or flange b³ sleeved upon shell or cylinder A, and screws or other means may be used to make 75 the engagement temporarily effective. The muffle-sections can be removed separately or together, and in the case the platinum heating-wire gets burned out by overheating the furnace or from other cause repair of the wire 80 can be made at once and the use of the furnace resumed by simply connecting up the broken ends by a suitable insertion.

By reason of the shape of the muffle the temperature of the furnace gradually increases 85 from front to rear, and a higher temperature is obtained at the rear or smaller end than at the front, although the temperature of the heating-wire is the same throughout its length, and hence this furnace can be placed 90 in an inclined or perpendicular position and used by jewelers as a crucible for fusing precious metals, as well as for other purposes requiring high temperature within a limited compass.

The outer section of the muffle is necessarily 95 of such high heat resistance that it will not fuse at any of the very high temperatures to which a furnace of this kind is subjected and to this end needs to have at least the quality 100 and endurance of the inner section. Experience has shown me that ordinary fire-clay will not suffice, because it fuses at a comparatively low temperature, as does also asbestos; but sections or parts made of Hessian sand will 105 stand the highest pressure and heat met with in these furnaces without being at all affected thereby. This also avoids the injury to the platinum wire which any fused jacket or covering will produce, because when fusing of 110 the covering occurs the wire is affected thereby, and particles adhere thereto and so embed it that it cannot be mended when burned out. This I wholly avoid by an outer muffle-section, which protects the wire in the particulars 115 just mentioned.

What I claim is—

1. In electrical dental furnaces, a two-part separable muffle having one part telescoped within the other and a heating-coil covered in 120 between said parts, substantially as described.
2. In electrical dental furnaces, a tapered muffle consisting of two sections telescopically and separably united and a heating-wire wound about the inner section and covered by 125 the outer section, substantially as described.
3. An electrical dental furnace comprising a muffle of tapered form smallest at its closed inner end and consisting of an electrically-wound inner section and an unwound outer 130

section fitting closely upon the inner section, said inner section having the winding removable therewith and exposed on the surface thereof for repairs, substantially as described.

5. 4. In electrical dental furnaces, a sectional muffle consisting of a plain outer section and an electrically - wound inner section nested within the outer section, and a non-conducting body having a cavity containing said muffle, substantially as described.

15 5. In dental furnaces, a body of a non-conducting material having a cavity in its end and a resistance-coil about said body, in combination with a separable two-part muffle occupying said cavity and an electrical winding about the inner part of the muffle connected with the said resistance-coil, substantially as described.

20 6. A dental furnace comprising a suitable casing, a body of non-conducting material therein having a cavity in one end and a resistance-wire wound about said body, in combination with a sectional muffle fitting said cavity, the outer section thereof being plain and the inner section wired about its outside

25 and connected up with said resistance-coil, and conductors for the electric current extending to the opposite end of said body, substantially as described.

7. In electrical furnaces, a suitable casing 30 and a non-conducting body therein and insulated therefrom, a resistance-coil about said body and conductors for the current extending through the same from end to end, in combination with a muffle consisting of telescopically-united sections inclosed in a cavity in said body and a heating-wire between said sections having one end connected with one of the terminals of the said resistance-coil and the other end with one of said conductors, 35 the inner end of said wire extending through the wall of the outer muffle-section, substantially as described.

40 In testimony whereof I sign this specification in the presence of two witnesses.

LUTHER L. BOSWORTH.
